Specification of Letters Patent. Patented Jan. 14, 1919.

Application filed March 23, 1918. Serial No. 224,178.

To all whom it may concern:

Be it known that we, EDWARD B. HESS and LEWIS C. MYERS, citizens of the United States of America, and residents of the borough of Brooklyn, in the city of New York, county of Kings, and State of New York, have invented certain new and useful Improvements in Type-Writing Machines, of which the following is a specification.

10 The present invention relates generally to typewriting machines and has more particularly reference to improved margin controlling devices, line locking and releasing mechanism, and bell ringing mechanism.

15 This invention is an improvement over the structures shown in applications filed by us July 13, 1917 and Oct. 27, 1917 and respectively numbered serially 180,261 and 198,775 in which visible margin controlling devices 20 in front of the platen, and above and in rear of the forwardly recumbent type bars, are used.

In the above mentioned applications there are disclosed margin rails in front of the 25 platen and on both sides of the printing center so arranged as to afford space between them for the passage of the type bars to the printing center together with complementary stop means between the transversely movable platen and the margin rails arranged so that the right hand margin controlling devices limit the movement of the platen in a left hand direction and the left hand margin controlling devices limit the movement 30 of the platen in a right hand direction. As there shown, the left hand margin rail is rigid and has a stop that coöperates with a stop block at the left hand side of the platen while the right hand margin rail is mounted

35 so as to partake of a rocking movement and carries a stop composed of two dogs with which engage a stop block, on the right hand end of the platen, that acts to effect a partial rocking of the margin rail by engagement

40 with the first dog and a more complete rocking motion of the margin rail by its engagement with the second dog, the bell ringing device being operated by the more limited movement of the margin rail while the line 45 lock means are operated on the more complete rocking movement of the margin rail. The stop block carried by the platen consists

of two members, spaced apart vertically, that coöperate in either lower case or shifted position with the transversely spaced dogs 55 of the stop member carried by the margin rail. In that device there is also provided suitable connecting means between the line lock, the bell ringing mechanism and the margin rail, the parts being so arranged that 60 there is a releasable connection that permits the line locking means and the margin rail to be restored separately while, at the same time, said connections are rigid when transmitting motion to the line locking means to 65 move the line locking means into locking position.

The main object of this invention is the production of a structure that lends itself more readily to the commercial embodiment 70 of the broad inventive idea disclosed in the previous applications, cited above; and more particularly in reference to a simplification of the complementary stop elements between the right hand margin rail and the platen; 75 and also to means for making connections between the margin rail, the line locking means and the bell ringing device as well as to the methods of mounting the margin rail itself, a rocking and a sliding movement 80 85 80 being imparted to the margin rail instead of two rocking movements of different amplitude, as in the previous applications.

One of the main features of the invention resides in so mounting the margin rail that it has both a rocking and a sliding movement, and in effecting line locking by means of the sliding movement of the margin rail, and in making possible the release of the line locking means by rocking the rail so as to 90 move the members of the stop element out of each other's path.

Another feature of the invention resides in imparting a rocking movement to the margin rail for effecting bell ringing and a 95 sliding movement to the rail for effecting line locking and, in addition thereto, operating means, independent of the platen, for rocking the margin rail to admit of the release of the line locking means. It will thus 100 be observed, that rocking of the margin rail serves two purposes, *i.e.* to operate the bell ringing mechanism and to admit of the release of the line locking means.

- Another feature of the invention resides in the interconnection between the actuating member, or margin rail, and the line locking means whereby the parts are connected for movement in response to endwise movement of the margin rail at all times, while admitting of an independent movement of the margin rail to admit of release of the line locking means and also for the purpose of bell ringing.
- The complementary stop means between the margin rail and the transversely movable platen preferably include a stop member on the margin rail consisting of two dogs spaced apart laterally and having oppositely tapered surfaces inclined away from each other, the taper surface on the right hand dog presenting the lowest portion of its taper to the advancing stop block so as to 15 rock the margin rail under the influence of the advance of said stop block and permit the rail to be restored abruptly after being rocked into its highest position; said second stop dog presenting an abrupt abutment surface to the advancing stop block so as to 20 transmit the endwise movement of the platen to the margin rail. The taper surface of said second stop dog is so arranged that its highest point is adjacent to the abrupt abutment surface so that, when the parts are 25 released, the margin rail will be restored gradually and without effecting a second ringing of the bell.

Other features of construction will appear as the specification proceeds.

The invention is embodied in the accompanying drawings in which—

Figure 1 is a top plan view indicating in a more or less diagrammatic form, the general construction of the machine to which the invention is applied and showing two margin rails, together with complementary stop elements and four of a series of type bars (indicated), three of which are shown 40 in a position of rest and one in printing position between the margin rails and against the platen, the keyboard being omitted.

Fig. 2 is a front elevation of the machine embodying the invention with the dust 50 sheds in section the ribbon spool removed, and with parts broken away, and shows more particularly the center card guide, its scale, the ribbon vibrator, a central type bar guide, and a type bar in printing position; and also 55 shows the relation of these elements to the margin rails and their stop elements.

Fig. 3 is a top plan view, largely diagrammatic in character, with parts omitted and broken away and shows more particularly 60 the relation of the margin rail, on the right hand side of the printing center, and its associated elements as bell ringing and line locking and releasing mechanisms.

Fig. 4 is a side view of the machine, partly 65 in elevation, partly in section, and partly

broken away, with elements omitted to illustrate the relation of the right hand margin controlling devices to the bell ringing, line locking and releasing mechanism, the parts being shown in the relation they normally 70 occur except that one type bar is shown in printing position.

Fig. 5 is a detail view of part of the elements shown in Fig. 4 showing the connections between the line locking and releasing 75 means and the bell ringing device; the stop block on the platen being released from the second dog on the margin rail by imparting a rocking movement to the margin rail. The carriage is here shown in its lower case 80 position.

Fig. 6 is a view similar to the parts shown in the upper right hand corner of Fig. 5 except that the margin rail is shown in its lowered position and the carriage in its 85 shifted position.

Fig. 7 is a plan detail view partly broken away and partly in section of the right hand margin rail and connections therefrom together with a stop block at the right hand 90 end of the platen.

Fig. 8 is a sectional view taken through the stop block adjacent the right hand end of the platen showing the means for adjustably securing the stop block, in position, 95 to the carriage frame.

Fig. 9 is a detail view, partly in section, of the left hand margin controlling devices.

1 indicates the general frame-work of the machine in which is mounted the carriage 100 raceway 2 supporting the carriage 3 and provided with case shifting mechanism indicated by the member 4 so that the carriage and its support may be raised or lowered in a manner well understood in the art. The 105 shift mechanism employed is that of the well known Royal typewriter, such as is described in Patent No. 1,227,438. Mounted in the carriage 3 is a platen 5 of any suitable construction and provided with a suitable line space advancing mechanism 6 in the usual manner. 7 indicates a segment on which are pivotally supported type bars 8 normally occupying a forwardly recumbent position with their free ends resting on a 110 head rest 9 located near the forward end of the machine. 10 indicates the key levers pivotally supported at 11 in a suitable bearing and connected by means of a vertical link 12 to a front link 13 connected to the 115 rear of a type bar by means of a link 14. To link 14 is secured a bar or link 15, the rear end of which is bent to engage a universal bar 16, link 15 being provided with a spring 17, the rear end of which is connected with 125 an adjustable rocking frame 18 and the front end of which is secured to a member 19 carried by link 14. It will be understood that all the type bars, when actuated, move to a common printing point or center. Adjacent 130

cent to the common printing point of the machine is a type bar guide 20 consisting of two converging members suitably mounted by means of a bracket 21 on a stationary part of the machine. Mounted to move with the carriage raceway 2, so as to partake of the case shifting movement imparted thereto, is a ribbon vibrator 22, a front card guide 23 and its scale 24. These elements are also located adjacent to the printing point and are intermediate the type bar guide and the platen. Inclosing the upper part of the machine are dust sheds 25 carrying ribbon spools 26.

27 indicates a margin rail located on the left hand side of the common printing center, and 28 indicates another margin rail located on the right hand side of the common printing center. These margin rails are conveniently supported, in this instance, on top of dust sheds 25 in front of a vertical line and below a horizontal line drawn through the axis of the platen below the normal position occupied by the ribbon vibrator and in front thereof, and also in front of the card guide and its scale. In fact, the margin rails, as here shown, are located in front of a vertical line tangent to the front face of the platen and below a horizontal line tangent to the underside of the platen. It will also be noted that the margin rails are above the series of type bars and over, and substantially in line with, the pivots of said type bars. In this case, therefore, the dust sheds also constitute supports in front of and below the platen and above a series of type bars for the margin rails.

Associated with the right hand margin rail is a stop element 29 adjustably mounted thereon and a stop element or block 30 mounted on the carriage. Said right hand margin rail is provided with pivot extensions 31 that project into suitable bushings 32 in a stationary part of the frame work in such manner that margin rail 28 has both a rocking and a lengthwise sliding motion. Extending from the lower side of rail 28 is a dependent controlling member 33 and attached at one end to said controlling member is a spring 37, the other end of which is anchored on dust shed 25, said spring tending normally to maintain the right hand margin rail in normal position,—that is to say, in its extreme position to the right, lengthwise, and in its lowered position with respect to its rocking motion. The spring therefore serves a double purpose, as indicated above. 38 indicates a line lock blade carried by a laterally extending bar 39 and normally out of the plane of locking surface 40 of key levers 10, as shown in Fig. 5, being urged into this position by a spring 41 anchored at one end 42 to the frame work and having its other end connected to member 43 of bar 39. 44 indicates a stop to limit

the downward movement of said line locking blade. Interposed between the controlling member 33 and the member 43 are suitable connections, which in the present instance, take the following form. 45 indicates a vertically extending rock shaft located below the dust shed and adjacent to the right hand side of the machine, being carried in suitable brackets, as 46. Connected to the lower end of said rock shaft 45 is an arm 47 between which and the member 43 is interposed a link 48. Secured to the upper end of rock shaft 45 is a bifurcated member 49 the outer end of which embraces controlling member 33. 49 is a margin release rod supported in bearings 50 and normally urged outwardly by means of a spring 51. This margin release rod carries at its inner end a pusher 49'. 52 indicates a bell suitably mounted within the machine on tie plate 53; and 54 is a hammer for the bell suitably attached to controlling member 33, as shown. The stop member 29 is in the form of a guide or carrying member 55 slideable upon the right hand margin rail 28 and is provided with a spring-pressed pawl 56 adapted to engage in notches 57 of said rail. The particular construction here is that the carrying member 55 is provided with a pivot 58 for receiving ears 59 of pawl 56. 60 indicates a spring that presses against the under side of a handle portion 61 and normally urges said pawl 56 into engagement with one of the notches or teeth 57 of the rail. The carrying member 55 of the stop member is provided with two dogs or cam members 62 and 63 projecting inwardly toward the platen and spaced apart laterally, as shown. Said dogs are provided with taper or cam surfaces 62' and 63' which are inclined in opposite directions away from each other. Dog 63 also has an abutment surface 63''. The relation of the cams, or dogs, 62, 63 is such that, when stop block 30 is advancing under the influence of the carriage or platen in a left hand direction, it first comes in contact with cam surface 62' thereby tilting or rocking margin rail 28 without shifting it endwise. As soon as the member 30 has passed the high point of taper surface 62', an abrupt release of the margin rail from its rocked position and into its lowered position will be effected. Upon further advance of stop block 30 in a left hand direction, it will encounter abutment surface 63'' thereby shifting margin rail 28 lengthwise in a left hand direction. The stop element 30, mounted to move with the carriage or platen, is provided with a latch 64 pivoted at 65 and having a coiled spring 66 that bears with one end against the latch 64 and with its other end against plate 67 of stop element 30. 68 indicates an adjustable stop carried by plate 67 for variably limiting the effective action of spring 130

- 66 so as to position latch 64 properly with respect to dogs 62 and 63 with which it engages. Plate 67 is mounted on the carriage frame 3 (and is therefore movable with the 5 platen) by means of set screws 69 that pass through slots 70 in plate 67, and which permit a forward and rearward adjustment of the parts in a manner that will be readily understood.
- 10 As the carriage moves to the left and approaches the end of its stroke as determined by the position of stop element 29, latch 64 will engage with cam surface 62, thereby tilting margin rail 28 without effecting endwise movement thereof. As soon as latch 64 has passed beyond the high point of taper surface 62', margin rail 28 will be abruptly released thereby permitting spring 37 to restore the parts to normal position.
- 15 The rocking of margin rail 28 by means of latch 64 engaging the taper surface 62' will cause the parts to assume the position shown in Fig. 5 where, it will be seen, controlling member 33 is moved into an inclined position lifting bell hammer 54. It will be noted, that in assuming this position, the member 33 is free to move through the bifurcated portion of arm 34 of vertical shaft 45. On the abrupt release of margin rail 28 20 by the passage of latch 64 over the high point of taper surface 62', gravity and the action of spring 37 will cause hammer 54 to descend quickly, thus sounding gong 52 and thereby informing the operator that the carriage is approaching the end of the line. The carriage now continues its movement to the left and latch 64 encounters the abutment surface 63'' thereby imparting a lengthwise sliding movement to margin rail 28 and, consequently, also to controlling member 33. The effect of this is that said controlling member 33 will carry the bifurcated end of arm 34 with it thereby rocking the upright shaft 45 and causing arm 47 to 25 exert a pull on connection 48 of sufficient amplitude to bring the line lock blade 38 beneath locking surfaces 40 of the key levers. The position that the parts occupy at this time is indicated in Fig. 3. It is now impossible to manipulate the key levers to bring the type bars to the printing point and the carriage has reached the end of its movement as determined by the position of margin stop 29. If, however, it is desired 30 to release the parts to admit of writing additional matter on the same line, the margin release rod 49, having on its inner end the pusher 49', is moved inwardly, as indicated in Fig. 5, being thus caused to engage controlling member 33 and thereby impart a rocking motion to margin rail 28 of sufficient amplitude to permit latch 64 to pass over the high point of abutment member 63''. It will thus be seen, that the rocking motion of the margin rail has two functions,

one to ring the bell and the other to release the complementary stop elements from each other when in the position described. As soon as the parts have been thus released, the pull of spring 37 will cause margin rail 28 to have a retrograde lengthwise movement thereby avoiding the necessity of keeping the margin release rod depressed. It will be understood that the margin rail 28 in being rocked for the purpose of releasing the stop elements will have raised hammer 54 and, to prevent the gong from striking the bell a second time during the cycle of the machine, a taper surface 63' is provided which, as the carriage continues its movement in a left hand direction, gradually permits spring 37 to restore the margin rail to normal position so far as its rocking movement is concerned. The descent of hammer 54 is therefore so gradual that no sound is heard when it finally reaches bell 52. The carriage may now, of course, be advanced to the left until the usual stop elements, not shown, come together. It is a characteristic feature of this construction 90 that the connection between the line locking means and the margin rail is always complete for the purpose of transmitting the endwise motion of said margin rail to the line locking means but that, nevertheless, 95 the independent rocking motion of the margin rail is possible for the purpose of bell ringing without effecting the position of the line locking means; also that this rocking motion is utilized for the purpose of releasing the abutment surface 63'' and latch 64 so as to admit of a retrograde endwise movement of the margin rail and thereby permit the line lock to restore itself. It will be observed that with the construction 100 disclosed, it is immaterial whether the carriage is in its lower case position, as indicated in Fig. 5, or in its shifted position, as indicated in Fig. 6, since, in either event, latch 64 will engage in a manner previously 105 described with dogs 62 and 63. It will further be understood that, owing to latch 64, the carriage may be moved to the right past the cam members 62 and 63 without effecting a tilting movement of the margin rail and without displacing said margin rail lengthwise since it has already been moved back into normal position by reason of spring 37, so that movement of the carriage to the right is uninterrupted and does not 110 actuate the bell ringing and the line locking means.

The left hand margin rail 27 is provided with vertical teeth or notches, as shown, and is adapted to support an adjustable stop element 74 that cooperates with a stop element 75 on the transversely movable carriage. The stop element 74 consists of a carrying member 76, slidably engaged on rail 27 and is provided with a stop dog 77 consisting, in 115

effect, of an adjustable screw. 78 indicates a pawl, the point of which enters the notches of the rail 27 and is provided with ears 79 overlying the upper and lower side of the 5 carrying member 76. Formed in said ears 79 are slots 80 into which extends a pin 81 on the carrying member 76, the pawl being normally urged into engagement with the notches on rail 27 by means of coiled spring 10 82 surrounding pin 81 said spring engaging with one end on a portion of the pawl 78 and with its other end on the carrying member 76. The pawl 78 is further provided with a handle or operating member 83, as 15 shown. When the handle is depressed against the action of spring 82, the point of pawl 78 becomes disengaged from the notches in the margin rail 27, and simultaneously therewith, the carrying member is 20 moved to the left so that pin 81 occupies a mid-position in slot 80. When the pressure on handle 83 is released, the end of pawl 78 enters the notch in rail 27, the pin 81 meanwhile remaining substantially in its mid-position in slot 80. When thereafter the 25 stop element 75 on the carriage engages the stop dog 77, as the carriage is moved to the right, the carrying member 76, and with it the dog 77, is moved to the right a distance 30 equal, substantially, to one letter space, its position being determined by the engagement of pin 81 with the end of slot 80, as shown more particularly in Fig. 1, thereby bringing the carriage to the right to the extreme limit of which the adjustment of the 35 stops admits. The stop member 75 is slidably mounted in the carriage 3 of the machine, in this instance, by means of slots 84 sliding on pins 85 attached to said carriage. 40 A spring 86, anchored on the frame 3 and connected with the inner end of member 75, normally urges said stop element 75 into its outermost position in the plane of stop dog 77. When the carriage is moved to the right, 45 it will continue its movement until the stop element 75 encounters stop dog 77; but, when moving the carriage to the left with the stop element 75 in a position between the printing point and the stop dog 77, said stop 50 element will be caused to move rearwardly due to the fact that its outer end is beveled, as indicated at 87, said bevel surface coming in contact with a corresponding bevel surface 88 carried by stop element 74. In case 55 it is desired to move the carriage in either direction without interference, stop element 75 may be withdrawn by engaging a handle portion 89 and moving the end of said stop element out of the plane of 74. 60 It will be noted that the left hand margin rail 27 is rigidly mounted on dust shed 25 and is therefore entirely different in its characteristics from that of the right hand margin rail 28. The reason for this will be apparent when it is understood that the left

hand margin control devices must register exactly; and their construction therefore must be of such nature that so-called "banking over" will not occur. This is especially necessary in view of the fact that when the 70 carriage is moved by the line space lever to its initial position, the operator will, at times, retract the carriage with considerable force. It will be observed that, so far as the relation of the stop elements 74 and 75 is 75 concerned, it is immaterial whether or not the carriage is shifted into lower or upper case position.

A characteristic feature of the invention is the scale indication used in connection with 80 the margin rails. This scale indication may be adjacent to, or, more conveniently, upon the top surface of the margin rails as shown. The scale indication on the left hand rail 27 begins with zero at the right hand end of 85 the rail and is continued up to say the letter space thirty; or, as shown, by extending the margin rail beyond the general outline of the dust shed up to letter space 40. Similarly, the scale indication on the right hand 90 rail 28 will, if the right hand margin rail is extended in the same manner, begin with forty-one and continue to such number as may be desired, say eighty; or, if the margin rails are made shorter, the intervening numbers, say from thirty-one to forty-nine may, 95 from a practical point of view, be omitted, since the stop elements are really only intended as margin stops in the true sense of the word.

The peculiar scale indication described is necessary when the stop elements are arranged as in the present case and where full visibility of the margin scale indication is desired.

In operation, the stop elements 74 and 29 are adjusted to desired position. The carriage or platen is then moved to the right, its transverse movement in that direction being limited by the left hand stop elements 74 110 and 75 but is unobstructed by stop elements 29 and 30 on the right hand side. The manipulation of keys 10 now causes the carriage or platen to travel to the left until the stop elements 29 and 30 on the right hand 115 side limits the movement to the left.

We claim:

1. Line locking mechanism comprising: a platen, a dust shed, visible margin controlling devices located above the dust shed and in front of the platen, a member connected to said margin controlling devices extending down through the dust shed, an upright rocker shaft below the dust shed connected with the downwardly extending member of 125 the margin controlling devices, line locking means, and means at the lower end of the rocker shaft connected with the line locking means.

2. A margin controlling device compris- 130

ing: a platen, a marginal rail, a stop on the margin rail, a stop block movable with the platen consisting of a supporting plate, a tilting latch carried by said supporting plate for rigidly engaging the stop on the margin rail during the left hand traverse of the platen and for yieldingly engaging the stop on the margin rail during the right hand traverse of the platen, a spring normally holding said tilting latch in its extended position, and means for varying the extent to which the tilting latch is moved by the spring.

3. A margin controlling device comprising: a vertically shiftable carriage supporting a platen, a margin rail stationary as regards the shifting movement of the carriage, a margin stop carried by the margin rail, a stop block having an uninterrupted contacting face adapted to coact with said margin stop both in lower case and shifted position, and means mounting said stop block to move vertically with the carriage to shift it with respect to the stop on the margin rail and rigidly as regards vertical movement independently of the carriage.

4. A margin controlling device comprising: a platen, a margin rail, a stop carried by the margin rail, a stop block movable with the platen and comprising a plate having a tilting latch, means for adjusting the position of the tilting latch and means for adjusting the position of the plate at right angles to the axis of the platen.

5. A margin controlling device comprising: a vertically shiftable carriage having a platen, a stop element mounted independently of the carriage and stationary as regards the shifting movement of the carriage, a latch having an uninterrupted contacting face adapted to coact with said independently mounted stop element both in lower case and shifted position, and means mounting said latch to move vertically with the carriage to shift it with respect to the independently mounted stop element and rigidly as regards vertical movement independently of the carriage.

6. A margin controlling device comprising: a vertically shiftable carriage having a platen, a stop element mounted independently of the carriage and stationary as regards the shifting movement of the carriage, a latch having an uninterrupted contacting face adapted to coact with said independently mounted stop element both in lower case and shifted position, and means mounting said latch to move vertically with the carriage to shift it with respect to the independently mounted stop element and rigidly as regards vertical movement independently of the carriage, said means including a pivot admitting of lateral turning of latch in one direction.

7. A margin controlling device comprising:

ing: a vertically shiftable platen, a stop element mounted independently of the platen and stationary as regards the shifting movement of the platen, a latch vertically movable with the platen to shift it with respect to the stop element mounted independently of the platen and engaging said stop element either in lower or shifted position of the platen, and means for adjusting the latch at right angles to the axis of the platen and laterally thereof.

8. A margin controlling device comprising: a vertically shiftable platen, a stop element mounted independently of the platen and stationary as regards the shifting movement of the platen, said member having two oppositely tapered surfaces located one behind the other longitudinally of the platen, and a stop element, vertically movable with the platen to shift it with respect to the stop element mounted independently of the platen, and engaging said two surfaces endwise in either lower or shifted position of the platen.

9. Margin controlling devices comprising: a margin rail having a rocking and an endwise sliding movement, an extension from said margin rail, a rotatably mounted forked lever embracing said extension to admit of the rocking of the rail without disengagement of lever and extension and to impart the endwise movement of the rail to said forked lever.

10. Margin controlling devices comprising: a margin rail having a rocking and an endwise sliding movement, an extension from said margin rail, a rotatably mounted forked lever embracing said extension to admit of the rocking of the rail without disengagement of lever and extension and to impart the endwise movement of the rail to said forked lever, and a spring connected to said extension for restoring the rail both with respect to its rocking and endwise sliding movement.

11. Margin controlling devices comprising: a margin rail having a rocking and an endwise sliding movement, an extension from said margin rail, a rotatably mounted forked lever embracing said extension to admit of the rocking of the rail without disengagement of lever and extension and to impart the endwise movement of the rail to said forked lever, means for effecting endwise movement of the rail, and means engaging with the extension from the margin rail to rock the latter to free it from the means for effecting endwise movement.

12. Margin controlling devices comprising: a margin rail having a rocking and an endwise sliding movement, an extension from said margin rail, a rotatably mounted forked lever embracing said extension to admit of the rocking of the rail without disengagement of lever and extension and to

5 impart the endwise movement of the rail to said forked lever, an upright rockshaft carrying said forked lever at its upper end, and line locking means connected to the 10 lower end of said rockshaft.

13. Margin controlling devices comprising: a margin rail having a rocking and an endwise sliding movement, an extension from said margin rail, a rotatably mounted forked lever embracing said extension to admit of the rocking of the rail without disengagement of lever and extension and to 15 impart the endwise movement of the rail to said forked lever, an upright rockshaft carrying said forked lever at its upper end, line locking means connected to the lower end of said rockshaft, means for effecting endwise movement of the rail, and means 20 engaging with the extension from the margin rail to rock the latter to free it from the means for effecting endwise movement of the rail.

14. Margin controlling devices comprising: a margin rail having a rocking and an endwise sliding movement, an extension from said margin rail, a rotatably mounted forked lever embracing said extension to admit of the rocking of the rail without disengagement of lever and extension and to 25 impart the endwise movement of the rail to said forked lever, a bell and a hammer acting against said bell and mounted on the extension from the margin rail.

15. Margin controlling devices comprising: a margin rail having a rocking and an endwise sliding movement, an extension from said margin rail, a rotatably mounted forked lever embracing said extension to admit of the rocking of the rail without disengagement of lever and extension and to 30 impart the endwise movement of the rail to said forked lever, line lock means connected to said forked lever, a bell, a hammer acting against said bell and mounted on the extension from the margin rail, means for 35 rocking the rail to effect bell ringing, means for effecting endwise movement of the rail to effect line locking, and means engaging with the extension of the margin rail to rock the latter to free it from the means for effecting endwise movement of the rail.

the latter to free it from the means for effecting endwise movement of the rail.

16. Margin controlling devices comprising: a margin rail having a rocking and an endwise sliding movement, an extension from said margin rail, a rotatably mounted forked lever embracing said extension to admit of the rocking of the rail without disengagement of lever and extension and to 45 impart the endwise movement of the rail to said forked lever, line lock means connected to said forked lever, a bell, a hammer acting against said bell and mounted on the extension of the margin rail, means for rocking the rail to effect bell ringing, means for effecting endwise movement of the rail to 50 effect line locking, means engaging with the extension of the margin rail to rock the latter to free it from the means for effecting endwise movement of the rail, and means for preventing bell ringing when the rail is 55 rocked by the means engaging with the extension from the margin rail.

17. Margin controlling devices comprising: a margin rail having a rocking and an endwise sliding movement, an extension from said margin rail, a rotatably mounted forked lever embracing said extension to admit of the rocking of the rail without disengagement of lever and extension and to 60 impart the endwise movement of the rail to said forked lever, an upright rockshaft carrying said forked lever at its upper end, line locking means connected to the lower end of the rockshaft, a bell, a hammer acting against said bell and mounted on the extension of the margin rail, means for rocking the rail to effect bell ringing, means for effecting endwise movement of the rail to 65 effect line locking, and means engaging with the extension of the margin rail to rock the latter to free it from the means for effecting endwise movement of the rail, and means for preventing bell ringing when the rail is 70 rocked by the means engaging with the extension from the margin rail.

Signed at the borough of Manhattan, city, county and State of New York, this 21st day of March 1918.
